UNITED STATES PATENT OFFICE

2,656,576

DIE CASTING MACHINE

William H. Schwartz, Cleveland, Ohio, assignor
to Lester Engineering Company, Cleveland,
Ohio, a corporation of Ohio

Application August 17, 1950, Serial No. 179,961

7 Claims. (Cl. 22—70)

1

The present invention, while relating generally as indicated to improvements in a die casting machine, is more particularly concerned with improvements in the gooseneck and nozzle construction and mounting thereof on the machine.

It is one principal object of this invention to provide in a die casting machine, a gooseneck assembly in which the gooseneck is slidably mounted in a sub-frame or yoke rigid with the machine frame for making possible the convenient clamping of the discharge nozzle of the machine between the gooseneck and the die block and for facilitating the removal of the gooseneck from the yoke for servicing thereof or for providing access to the nozzle.

Another object of this invention is to provide a novel guiding and supporting means for the discharge plunger of the gooseneck assembly which assures accurate alignment between the plunger and the cylinder bore in which said plunger reciprocates.

Another object of this invention is to provide a unique separable coupling connection between the discharge plunger and the actuating piston therefor.

Another object of this invention is to provide a gooseneck unit which is entirely independent of the furnace and the melting pot therein.

Another object is to provide a simple adjustment for locking the gooseneck and nozzle against the die rigidly while permitting rapid unlocking for removal of the gooseneck; also replacement of the nozzle.

Another object of this invention is to provide an electrically heated, pyrometrically controlled, nozzle clamped between the gooseneck and the die block of a form such that the nozzle itself is at all times in intimate heat conducting relation with a surrounding heating element whereby to assure a maximum transfer of heat from the element to the nozzle.

Other objects and advantages of my invention will appear as the description proceeds.

To the accomplishment of the foregoing and related ends, said invention then comprises the features hereinafter fully described and particularly pointed out in the claims, the following description and the annexed drawing setting forth in detail one illustrative embodiment of the invention, this being indicative, however, of but one of the various ways in which the principle of the invention may be employed.

In said annexed drawings:

Fig. 1 is a vertical cross section view of the furnace end of a die casting machine illustrating

2

the gooseneck and nozzle constituting the present invention;

Fig. 2 is a vertical cross section view taken substantially along the line 2—2, Fig. 1;

Fig. 3 is a top plan view partly in section, such section having been taken along the line 3—3, Fig. 2; and

Fig. 4 is a cross-sectional view taken substantially along the line 4—4, Fig. 1.

Referring now more specifically to the drawings, the reference numeral 1 indicates the main frame of the die casting machine adjacent one end of which the furnace 2 is adapted to be positioned, the upper end only of the furnace being shown in the drawings, and if desired, said furnace may have casters or the like thereon to enable convenient transportation thereof from one machine to another.

Supported in said furnace 2 is a melting pot 3 which includes a generally cup-shaped reservoir 4 for molten metal and into which metal billets are adapted to be loaded for melting and a shallower and narrower extension 5 disposed closely adjacent the end of the machine frame. The shaping of the melting pot as indicated to provide a relatively deep cup-shaped portion 4 and with a relatively narrow and shallow radially projecting extension portion 5 enables the melting of a relatively large volume of metal and periodical loading of the melting pot with billets without possibility of damage to the gooseneck immersed in the metal and without appreciably reducing the temperature of the molten metal around said gooseneck. This construction of melting pot also prevents the expansion of the metal during the melting from imposing strains on the gooseneck.

Securely bolted to the machine frame 1 between suitable spaced extensions 6 thereof as by means of bolts 7 is a yoke 8 which is formed with downwardly depending legs 9—9, said legs being formed with opposed longitudinally extending guideways 10—10 disposed directly above the narrow and shallow portion 5 of the melting pot 3. Said yoke 8 may further be provided with a diagonal brace 11 and other braces 12 bolted as at 14 to the machine frame 1 for imparting vertical and lateral rigidity to said yoke 8.

Horizontally slidably mounted in the guideways 10—10 in said yoke 8 is a gooseneck 15 which includes oppositely-extending rib-like portions 16 slidably fitting in such guideways. Said gooseneck extends downwardly into the narrow and shallow portion 5 of said melting

pot 3 and such lower portion is formed with a vertically-disposed bore 17 formed in the liner 18 of suitable material in said gooseneck and a passageway 19 leading from the lower end of the bore 17 and curving upwardly and toward the machine frame 1, the upper end of such passage terminating in a duct having a spherical end portion 29 to fit within a corresponding spherical socket in the outer end of a discharge nozzle 21. Laterally through the lower portion of said gooseneck 15 and liner 18 and above the lower end of bore 17 is an inlet opening 23 through which molten metal from pot 3 may run into such bore 17 and into the curved passageway 19.

The nozzle 21 just referred to has a spherical discharge end 24 which is adapted to be fitted into a complementary socket formed in the adjacent one of a pair of separable die blocks, not shown, into registry with a sprue passage in said block which leads to the die cavity formed between separable die blocks. The nozzle 21 is provided with a passage 25 axially therethrough through which molten metal is adapted to be forced from the bore 17 and passage 19 in gooseneck 15 into the cavity formed between the separable die blocks. Said nozzle 21 has a tapered outer surface 26 throughout its length which is wedged into the correspondingly tapered bore 27 of the tubular body 29 in which an electric heating element 28 is disposed. By so wedging said nozzle 21 into the tubular body 29, the resulting expansion of said body 29 will preclude formation of an air gap between said nozzle and body at elevated temperatures. Because of the tapered wedge fit of the nozzle 21 in body 29 and initial stressing of said body member, the subsequent heating of the nozzle and body by current flow through element 28 will only relieve or partially relieve such stress in said body whereby said nozzle 21 and body 29 will at all times remain in intimate heat conducting relation.

Clamping of said gooseneck 15 in operating position with nozzle 21 clamped between said gooseneck and the adjacent die block is effected as by means of a pair of screws 30-31 which are carried in a bracket 31 mounted on the frame extensions 6 and have inner swivelled ends 33 bearing against the outer end face of said gooseneck 15. In turn, said bracket 31 is bifurcated at its opposite ends as at 32 and pins 34 pass therethrough and through ears 35 extending into the bifurcated ends, said ears 35 being formed as on the outer ends of the frame extensions 6 whereby, when it is desired to remove said gooseneck 15 for servicing the same or for replacing the same or for servicing the nozzle 21, one of said pins 34 may be withdrawn from the bracket end 32 and ear 35 and the bracket 31 swung clear about the remaining pin 34 so that the gooseneck 15 as a whole may simply be retracted away from the end of the machine frame 1 and completely removed simply by outward movement relative to yoke 8 to disengage guide ribs 16 from guideways 10 in said yoke.

The upper end of said gooseneck 15 is provided with a split guide unit 36 in which a portion of a discharge plunger 37 is slide guided, the lower end portion of said plunger 37 being closely fitted into the vertically disposed bore 17 whereupon, during the downward movement of said plunger, molten metal will be forced from the bore 17 through the curved passage 19 and through the nozzle passage 25 into the die cavity and, of course, upon raising the plunger to expose the

lateral opening 23, the molten metal from within the melting pot 3 will run through such lateral opening to fill the space beneath the bottom end of said plunger 37. It is to be noted that the guide bushing 38 in said split guide unit 36 is also of a split form. Said guide unit 36 comprises a half-section 39 carrying the bushing half-section 40, said section 39 being formed with openings fitting over upward extensions of screws 41 in said gooseneck 15. The other half-section 42 of said unit 36 carrying the other bushing half-section 43 is pivotally connected to section 39 at one side by means of a vertical pivot 44 and the other sides of sections 39 and 42 are releasably held together by a swing bolt 45 carried for vertical pivoting on section 39 and having a nut 46 engaging section 42.

Thus, it is apparent that by loosening the nut 46 on said swing bolt 45 the latter may be swung about its vertical pivot out of engagement with section 42 whereby said section 42 and the bushing section 43 carried thereby may be swung outwardly to release said discharge plunger 37 to enable transverse movement thereof with respect to the machine frame 1 and also with respect to gooseneck 15 upon raising of said plunger sufficiently to withdraw the lower end portion from bore 17.

The upper end portion of said discharge plunger 37 is formed with a collar or flange 47 which fits into a transverse T-slot 48 across the lower end of a split coupling 49, such T-slot extending in a direction parallel to the guideways 10 formed in said yoke 8. Such coupling 49 is connected to the lower end of the piston rod 50 of a hydraulic actuating cylinder 51, the latter being bolted directly to the upper end of said yoke 8. Said connection between said piston rod 50 and said coupling 49 comprises a head 52 on said piston rod fitting in a complementary recess in said coupling. Said coupling 49 is of the split type including two half sections 53 and 54, each pivotally connected at one side to a vertically disposed rod 55 depending downwardly from the upper end of said yoke 8 and one section 53 has, on its other side, a swing bolt 57 with a nut 58 thereon which is engageable and disengageable with a bifurcated ear 59 extending from the other side of the other section 54. Here again, upon loosening of the nut 58 on said swing bolt 57, said bolt may be swung out of engagement with the bifurcated ear 59 whereby the two sections 53 and 54 may be swung open to disengage the same from the head 52 attached to the piston rod 50.

A further feature of this invention is that when the piston 60 which is connected to the upper end of rod 50 and which is reciprocable in cylinder 51 is in its elevated position as shown in Fig. 1, the split guide unit 36 and the split coupling 49 both may be opened, the plunger 37 then being free to be raised to withdraw the lower end thereof from the bore 17 in said gooseneck 15 whereby said plunger may be transversely withdrawn from the machine independently of the gooseneck. Of course, because of the T-slot 48 the rod 50 and plunger 37 may be misaligned without interfering with free reciprocation of said plunger and by opening bracket 31, the entire gooseneck assembly may be transversely withdrawn from yoke 8 and the plunger disengaged from the closed coupling 49.

The hydraulic actuating cylinder 51 is of a conventional form including a suitable packing 61 at the lower end through which the piston rod

50 extends and having ports 62 and 63 at opposite ends through which fluid under pressure may be alternately admitted to effect reciprocation of the piston 60 (therein in opposite directions in accordance to which of said ports fluid under pressure is admitted).

A further feature of this invention is that rigid piping is employed throughout as distinguished from flexible hoses which are presently used on machines of this type. Thus, an elbow 64 for example is connected directly to port 63 with a one-way flow restrictor valve 65 connected to the other end of said elbow and metal tubing 67 connected to the one-way flow restrictor valve through the intermediary of the usual clamping nut 68 which clamps the flared end of the tube against a conical seat formed in the valve body. Thus, when fluid under pressure is admitted into the tube 67, the valve member 69 is unseated, overcoming spring 10, and the fluid freely flows into the upper end of said cylinder 51 thereby forcing said piston 60 downwardly and through the coupling 49 forcing the discharge plunger 37 downwardly to effect discharge of molten metal from the gooseneck 15 and through nozzle 21 into the die cavity. The fluid displaced from the lower end of said cylinder 51 is returned to a suitable reservoir through the tube 71 connected to the port 62 as by the fitting 72 and having therein a suitable throttle valve 73 operated by the lever 74. Of course, the tubes 67 and 71 will be connected to a suitable four-way reversing valve (not shown) or the like so that when it is desired to raise the piston 60 and thus the discharge plunger 37 through the split coupling 49, fluid under pressure admitted into the tube 71 will force said piston 60 upwardly to raise said discharge plunger 37, the fluid displaced from the upper end of said cylinder 51 now passing through the orifice 75 in the seated valve member 69 and through the tube 67 into a suitable reservoir, not shown, the size of the orifice 75 controlling the rate of upward movement of said piston 60 to keep such movement within desired limits.

In summary, it can now be seen that the present construction is of a very simple form, providing accurate guiding of said discharge plunger 37 and enabling servicing and replacement thereof, independently of the gooseneck 15 and providing for accurate positioning of said gooseneck 15 with respect to said discharge nozzle 21 and through which firm clamping of the nozzle 21 between the die block and the gooseneck 15 may be readily accomplished. In addition, said gooseneck 15 is independent of the melting pot 3 and can be readily removed or replaced simply by releasing and swinging said bracket 31 and sliding said gooseneck 15 out of engagement with its supporting yoke 8. Moreover, said gooseneck 15 is disposed to one side of said melting pot 3 whereby there is no danger of damage to the same when loading metal billets into the melting pot and in so loading the melting pot only the molten metal will ever be in contact with the gooseneck whereby the same is not subjected to wide variations in temperature and is not subjected to any strains incident to the loading of the melting pot with the billets.

A still further notable feature of the present construction is that the transversely slidable connection of the rod 59 and said plunger 37 enables free reciprocation of the latter without locking strains on the gooseneck and plunger even though the rod and plunger are misaligned

5 basis apt to occur by reason of variation in the operative position of the gooseneck due to variation in the length of the nozzle 21 and variation in the distance from the axis of bore 17 to spherical portion 20 for example.

Still another important feature is the application of clamping force on said gooseneck by screws 30 which are directly opposed to the nozzle 21 thereby eliminating eccentric forces on said gooseneck. The proper setting of these screws 30 is a simple matter, and is the only adjustment that requires to be made by the operator in setting up the machine.

While as illustrated and described above, the gooseneck 15 and guide unit 36 are made up of several parts, it should be explained that this is merely to facilitate the manufacture of the complete assembly. In other words, from the operative standpoint such gooseneck and guide unit are to be considered as in effect integral, the plunger 37 being held securely in proper alignment, irrespective of the removal and replacement of the assembly in the guideways 10-10.

The foregoing construction not only insures the proper mounting of the gooseneck assembly in the machine, since this can be accomplished in only one way, but also the proper alignment of the operating parts in such assembly is at all times assured.

Other modes of applying the principle of the invention may be employed, change being made as regards the details described, provided the features stated in any of the following claims or the equivalent of such be employed.

I, therefore, particularly point out and distinctly claim as my invention:

1. In a die casting machine, the combination of a frame, means adjacent one end of said frame providing a passageway for molten metal, a yoke with downwardly depending legs fixedly secured to such one end of said frame, a gooseneck slidably carried by said yoke for movement toward and away from said means into and out of engagement therewith, said gooseneck being formed with an upwardly opening bore adapted to contain molten metal and with a passage communicating such bore with the passageway in said means when said gooseneck is in position engaging said means, a clamp device movable with respect to said yoke and frame in the direction of sliding of said gooseneck into engagement with said gooseneck at a point substantially aligned with said means to retain the gooseneck in position engaged with said means and out of engagement with said gooseneck to permit movement of the latter away from and out of engagement with said means, an upwardly extending plunger reciprocable in such bore for displacing molten metal therein through such passage and passageway, an actuator for said plunger mounted on said yoke, and a coupling between said plunger and actuator, said coupling having a transversely slidable and detachable connection with said plunger whereby said gooseneck with said plunger therein may be moved toward and away from said means upon manipulation of said clamp device.

2. A gooseneck assembly for the furnace and melting pot end of a die casting machine comprising a yoke formed with downwardly depending legs and adapted for mounting in fixed position above such pot, a gooseneck depending from such yoke for immersion in molten metal in such pot and having a transversely slidable connection with such legs and formed with an upward-

ly opening bore adapted to receive molten metal from the pot and with a discharge passage leading from such bore to an outlet transverse to the path of sliding of said gooseneck, a plunger vertically reciprocable in such bore and extending upwardly between such legs, a split plunger guide mounted on said gooseneck to embrace a portion of said plunger which is axially spaced from such bore, said guide being openable to permit transverse withdrawal of said plunger.

3. A gooseneck assembly for the furnace and melting pot end of a die casting machine comprising a yoke formed with downwardly opening legs and adapted for mounting in fixed position above such pot, a gooseneck depending from such yoke for immersion in molten metal in such pot and having a transversely slidable connection with such legs and formed with an upwardly opening bore extending upwardly between such legs adapted to receive molten metal from the pot and with a discharge passage leading from such bore to an outlet transverse to the path of sliding of said gooseneck, a plunger vertically reciprocable in such bore and extending upwardly between such legs, a hydraulic cylinder fixedly mounted on the upper end of said yoke, a piston vertically reciprocable in said cylinder and having a piston rod extending downwardly between such legs, and means providing a transversely slidable connection between said piston rod and plunger whereby said plunger and gooseneck may be transversely moved between such legs with respect to said piston rod.

4. A gooseneck assembly for the furnace and melting pot end of a die casting machine comprising a yoke formed with downwardly depending legs and adapted for mounting in fixed position above such pot, a gooseneck depending from such yoke for immersion in molten metal in such pot and having a transversely slidable connection with such legs and formed with an upwardly opening bore extending upwardly between such legs adapted to receive molten metal from the pot and with a discharge passage leading from such bore to an outlet transverse to the path of sliding of said gooseneck, a plunger vertically reciprocable in such bore and extending upwardly between such legs, a hydraulic cylinder fixedly mounted on the upper end of said yoke, a piston vertically reciprocable in said cylinder and having a piston rod extending downwardly between such legs, and means providing a transversely slidable connection between said piston rod and plunger whereby said plunger and gooseneck may be transversely moved between such legs with respect to said piston rod, said last-named means comprising a coupling secured to said piston rod and formed with a transverse T-slot, and said plunger being formed with a collar portion transversely movably fitting into such slot.

5. In a die casting machine, the combination of a frame, means providing a pasageway for molten metal, a yoke fixedly secured to said frame, a gooseneck slidably carried by said yoke for movement toward and away from said means into and out of engagement therewith, said gooseneck being formed with a chamber adapted to contain molten metal and with a passageway communicating such chamber with the passageway in said means when said gooseneck is in position engaging said means, releasable clamping means bearing on said gooseneck to retain the latter in position engaged with said means, a plunger reciprocable in said gooseneck to displace molten metal from such chamber through such passageways, plunger actuating means including a cylinder mounted in fixed position with respect to said frame and said yoke and a piston reciprocable in said cylinder, and a coupling securing said piston and plunger together whereby the latter is reciprocated by the former, said coupling having a transversely slidable connection between said plunger and said piston to assure free reciprocation of said piston in said cylinder and of said plunger in said gooseneck in the event of misalignment of said piston and said plunger when said gooseneck is clamped in position engaging said first-named means.

6. The die-casting machine according to claim 5 characterized further in that said plunger is transversely detachable from said coupling whereby said gooseneck and plunger may be withdrawn as a unit from said yoke.

7. The die-casting machine according to claim 6 characterized further in that said gooseneck is provided with a split guide for said plunger of which guide a portion is integrally formed with said gooseneck for insuring accurate guiding of said plunger relative to said gooseneck and for enabling transverse disassembly of said plunger from said gooseneck and from said coupling without first removing said gooseneck from said yoke.
